SUPERVISORY SIGNALING SYSTEM

Dwight W. Bleser, Edgewater, N. J., and Francis C. Evans, Dongan Hills, N. Y., assignors to American District Telegraph Company, Jersey City, N. J., a corporation of New Jersey

Application November 21, 1942, Serial No. 466,516

3 Claims. (Cl. 177—311)

This invention relates to improvements in supervisory signaling systems and more particularly to such systems especially adapted for use in connection with burners, boilers, and the like, utilizing oil or other fluid fuel.

In the operation of burners, boilers and the like, as aforesaid, several conditions of a dangerous nature can arise. While such installations are usually provided with safety controls which, once operated, make necessary manual restarting of the unit, still the possibility exists that these controls may fail to function and in so doing fail to prevent the existence of such conditions. Should there be a failure of proper ignition of the fuel at an attempted start of operation of the unit, and should the safety controls fail to arrest fuel feed, there would be a strong possibility of a dangerous explosion in the event of a delayed or subsequent ignition of the accumulated fuel in the fire-box. Even more dangerous, however, would be a condition in which ignition and combustion of the fuel failed during unit operation and after the usual starting period, and fuel feed into the hot fire-box was continued. Supervision over the operation of a plurality of installations of this character can be accomplished from a central station if suitable means be provided at each unit for automatically transmitting to that station some code signal denoting the existence of the foregoing and other conditions that require immediate attention. Such attention can be provided by the dispatch of a service attendant from the station. Other conditions at each unit, of which the station can be apprised by code signals, are excessive steam pressure, lack of water or low water, unduly low temperature, and, if desired, supervision of a still further nature likewise can be carried out.

Accordingly, an object of the invention is to provide means for causing transmission of code signals in responsive to abnormal conditions in a unit utilizing oil or other fluid fuel.

Another object of the invention is to provide, in combination with a code transmitter, control means set in operation at each start of unit operation, said control means being operative to cause transmission of code signals in response to abnormal unit conditions and to prevent transmission of signals when unit conditions are normal.

Another object of the invention is to provide, in combination with a code signal transmitter, control means for the transmitter, said control means being associated with the burner unit in such fashion as to begin a cycle of operation at each starting of the unit, such cycle being con- 55

cluded in transmission of signals in the event the unit operation is abnormal at the end of a predetermined time interval.

5 A further object is to provide means whereby the time interval of cyclic operation of the control means preceding transmission of signals can be varied.

10 A still further object of the invention is to provide means for interrupting the cyclic operation of the control means in the event the unit operation is normal whereby transmission of signals is prevented.

15 Another object of the invention is to provide means whereby code signals are transmitted automatically substantially instantaneously upon the occurrence of certain abnormal conditions of a unit of the type before described.

20 An additional object of the invention is to provide means whereby distinctive code signals are transmitted when the safety controls of a unit have operated, or when a power failure of more than a predetermined duration has occurred.

25 An ancillary object of the invention is to provide apparatus, associated with the controls of a unit of the type previously described, operative to transmit a code signal upon the failure of fuel ignition and combustion within a predetermined interval after start of the unit, and also upon failure of fuel ignition and combustion during a 30 period in which the same must occur as a requisite of successful safe operation.

35 In carrying out the foregoing and other objects of the invention, it is contemplated that code signaling mechanism can be associated with the normal control system of a fluid fuel unit of the type previously described. To this end, use is made of a code transmitter of well known type adapted to be operated for the transmission of a code signal of one length upon the deenergization of the holding coil of the transmitter and to transmit a code signal of another length upon reenergization of such holding means. The holding means can be deenergized instantaneously upon the occurrence of several abnormalities existent in the operation of the unit and also can be deenergized within a predetermined time interval after the start of operation of the unit should there be a failure of fuel ignition and combustion. In addition, a second transmitter for code signals 45

50 can be associated with the system, such transmitter being similar to the first transmitter but being deenergized upon the opening of switches of a nature providing certain other supervisory functions.

The control means utilized for deenergizing the

first transmitter upon failure of fuel ignition and combustion can have the time interval of operation thereof varied as may be desired to fit existing circumstances, and operating mechanism is included in this control means for preventing de-energization of the first transmitter upon the ignition and proper combustion of fuel within the delay time interval. The component parts of the control means will be described hereinafter in detail as well as the operation of the code transmitters associated therewith.

Other features, objects, and advantages of the invention will become apparent by reference to the following detailed description of the accompanying drawing, wherein Fig. 1 is a schematic circuit diagram of a supervisory signaling system embodying the invention, and

Fig. 2 is a representation of the principal parts of a transmitter used in this invention.

Referring now to the drawing, 19 indicates generally a code transmitter of well known type. This transmitter briefly described comprises a spring-motor driven rotary wheel 11 normally held against rotation by a holding coil 12. The wheel 11 has a plurality of teeth or projections thereon with their path of rotation so disposed relative to a spring contact member 14 that rotation of the wheel causes intermittent breaking of a circuit, closed by the contact 14, in accordance with the number and spacing of the teeth. This circuit, which includes the lines 15 and 16, extends to a central office with a second transmitter, indicated generally at 17, in series with the first transmitter. The transmitter 17 is similar in construction to that previously described, with the exception that a different number of teeth in different spacing may be employed on the wheel thereof.

These transmitters are of the type in which deenergization of the holding coil 12 releases the wheel 11 for rotation and, under the control of suitable cam means, such rotation continues until the wheel has rotated through two complete circuits or rounds, at the completion of which the wheel is locked against further rotation. The cam means is of such nature that, when the coil 12 is reenergized, the wheel is released for one circuit or round of rotation. A transmitter of the foregoing type which is well known to the art has been illustrated representatively in Fig. 2 wherein it will be seen that use is made of a pair of holding coils 12 operating an armature 60 having a depending portion 61 at the lower end of which is located a cam follower 62. The follower 62 rides in a cam slot 64 cut in a cam wheel 65. The outer wall of this slot 64 has a recess 66 therein and the inner wall likewise has a recess 67 there-in spaced apart in the direction of rotation of the cam wheel substantially 240°. Cam wheel 65 is adapted to be driven by the usual spring motor 68 fastened to the shaft 69 to one end of which is a gear 70 meshed with a gear 71 on the same shaft with the toothed wheel 11. The ratio of gears 70 and 71 is approximately three to one so that one complete revolution of cam wheel 65 causes three revolutions of code wheel 11. Normally when the coils 12 (one of which would be sufficient) are energized, the cam follower 62 is retained in the recess 66, locking the cam wheel and consequently wheel 11 against rotation. When coils 12 are de-energized, the member 61 falls due to gravity, dropping the follower 62 out of the recess 66 into the slot 64, permitting clockwise rotation of the cam wheel until the follower 62 drops into the recess 67. This will occur when the code wheel

11 has made two complete revolutions. Likewise, when the coils 12 are again reenergized, the follower is elevated, bearing against the upper wall of the cam slot until recess 66 is again in line with the follower, at which time the follower is moved into this recess, locking the transmitter in normal condition. This latter arc of movement of approximately 120° results in one complete revolution of the code wheel 11.

Direct current for maintaining the holding coil 12 energized is supplied from a source of direct current, usually a local battery, or its equivalent, indicated by the plus and minus signs, by line 21, through three switch mechanisms in series, contact A1 of relay A, through the coil 12 to the return line 22. The three switches just mentioned comprise a low water cut-off switch mechanism, a pressure switch mechanism operable to open its contacts upon excessive steam pressure, and a thermostat mechanism adapted to open its contacts when room temperature or the like drops below a predetermined minimum. Devices of this nature are well known and hence have been indicated diagrammatically only. Direct current for maintaining the holding coil of transmitter 17 energized is supplied from the same source through line 21 and through a plurality of supervisory devices through this coil again to the return line 22. These supervisory mechanisms may be of various natures, such as an aquastat, a power phase failure indicator, or other equipment of a nature customarily employed in connection with burners of this type.

A direct current circuit can also be established from the same source through a flame detector device, line 24, winding B2 of relay B, to the return line 22 for a purpose to be explained later. The flame detector device may be of any well known character, such as a thermostatic heat detector usually inserted in the stack of the unit and utilized with intermittent flame type burners, a stack switch of similar type usually used with intermittent modulated flame type units, a radiant energy detector ordinarily set in an opening in the fire-box or ash pit of the unit, a photo-electronic flame detector usually installed in an opening in the fire-box or ash pit of a unit, or a sensitive thermostatic element designed to be mounted in an opening of the fire-box or ash pit. Inasmuch as devices of this character are well known to the art, illustration of any particular one thereof has been omitted, since all operate on the principle of closing a circuit under certain conditions, i. e., satisfactory ignition and combustion of fuel.

The time delay mechanism utilized in this invention for cooperation with the transmitter 10 at the start of operation of a unit and during operation thereof, so far as flame detection is concerned, is shown as being made up in part of a vacuum tube 25 which has two similar sections S1 and S2. Since these sections are similar and each acts independently of the other, they constitute in effect two separate vacuum tubes in the same glass envelope. The only common element within this envelope or tube 25 is the filament, which can be energized either by a secondary winding 26 of transformer 27 when a supply source of 110 volts A. C. is used, or also energized by winding 26 and the secondary 28 when a 220 volt source is used. In addition to the transformer 27, use is made of a transformer 30, the primary of which is in effect a center-tapped primary with the top part thereof being used on 110 volt power and the entire primary being used on 220 volt power. In the il-

lustrated equipment 110 volt power only is used, though connections have been shown for 220 volt work. Accordingly, the following description and reference to the two transformers will be made on the basis only of 110 volt operation.

The primary of transformer 30 is connected in series with the burner motor M across the power supply line (a source of A. C.) in such a way that the closure of the burner motor starting contacts 31 will shunt the primary of transformer 30. Contacts 31 are closed by relay R which can be energized through the secondary of a transformer connected to the power supply line through the control thermostat CT which is the thermostat operating a burner unit to control the demand for heat. When the unit is at rest with the contacts 31 open and with the source of A. C. functioning properly, a voltage will be induced in the secondary of transformer 30. This voltage is impressed between a tap 32 on the upper part of the secondary winding of transformer 27 and the grid of section S1 of the tube 25. Each section of tube 25 has such characteristics that the respective grids do not draw current and consequently, even though a connection is made between the secondary of transformer 30 and the grid of section S1, there will be no load on this secondary of the transformer. The upper half of the secondary winding of transformer 27 is connected to the lower half of that winding, i. e., the plate voltage winding of the transformer at the point to which is connected the line 35, termed the return wire. The lower end of this plate voltage winding is connected by line 36 to the two plates of sections S1 and S2 of tube 25. The voltage of that portion of the secondary of transformer 27 in series with the secondary of transformer 30 is opposite in phase to the transformer 30 secondary. The purpose of this arrangement is to drive the grid of section S1 more negative when the voltage applied by the secondary of transformer 30 is removed. With this secondary voltage of transformer 30 acting between the return wire 35 and the grid in this manner, the grid becomes sufficiently positive on each positive half cycle to permit current to flow through section S1 of the tube from plate to cathode. This current is sufficient to energize relay B through its left winding B1 over a circuit including contact 33 and to charge condenser 37 sufficiently for this condenser to maintain winding B1 in holding condition during the negative half cycles in which no current is passed by section S1. The condenser 37 may be of the order of, say, 40 microfarads. Windings B1 and B2 of relay B are of additive effect.

As before stated, since the two sections of tube 25 are of such character that their grids do not draw current, the result is that the only current existing in the primary of transformer 30 is a small magnetizing current which is of considerably lower value than the current necessary to operate the motor M even if that motor be of the smallest size used in units of this character. As a further protection, a fuse 38 of value considerably lower than that necessary for the operation of the motor M is provided for protection in the event the primary of transformer 30 should become shorted.

The circuits are connected to the section S2 of tube 25. One of these circuits includes an eight-point switch 40, a resistor 41 of, say, 600,000 ohms, a condenser 42 of the order of 40 microfarads, and the grid of section S2. The other circuit includes relay A, resistor 44 of the order of 15,000 ohms,

condenser 45 of the order of 20 microfarads, and the cathode of section S2. Between these two circuits is a connecting link, indicated by line 46, contact 47 of relay B, line 48, and resistor 49 of the order of 500 ohms. These two circuits combine to provide the retard or delay period attendant upon the operation of transmitter 10 in association with the flame detector.

Due to the connection between the two circuits of section S2, which connection includes the contact 47 of relay B and the resistor 49, the switch 40 and consequently the grid of section S2 are kept essentially at the same potential as the cathode of this section. The resistors between the grid and the switch point to which the switch arm 40' may be connected have no effect on the voltage of the grid for the reason, as explained previously, that the grid of this type of tube does not draw current. Consequently, with the grid of section S2 maintained at the cathode potential in this manner, sufficient current flows from the plate to the cathode of section S2 on each positive half cycle of the plate voltage to energize relay A and charge condensers 42 and 45. Condenser 45 discharges on the negative half cycles through the resistor 44 and relay A and, since resistor 44 is of the order of 15,000 ohms, and condenser 45 is of the order of 20 microfarads, the discharge period thereof is sufficiently long to keep relay A from chattering.

Condenser 42 on the negative half cycles discharges through a portion of switch 40 and resistance 41, the latter resistance, as before mentioned, being in the nature of 600,000 ohms. This resistance is so high, therefore, that the amount of discharge of condenser 42 is negligible, and hence it may be assumed that this condenser remains charged. In addition, each section between the taps of switch 40 is of the nature of 50,000 ohms so that, depending on the position of the contact arm 40', the resistance through which condenser 42 can discharge may be increased or decreased, it being understood that the total time necessary for discharge of the condenser may be increased by cutting in additional resistor sections of switch 40. The potential of the charge on condenser 42 is equivalent to the voltage drop caused by the current flow through relay A and resistor 44, and is positive at the cathode end and negative at the return wire 35.

Under certain conditions a branch circuit can be established whereby the winding B1 of relay B can be energized. This circuit extends from the cathode of section S1 through the contact A2 of relay A (when relay A is deenergized), line 55, to and through winding B1 to return line 35.

The use and operation of this supervisory control system in relation to the operation of the burner unit will be described, first, during normal operation of the unit under the heading "Normal operation," then under such circumstances of abnormality as result in the transmission of two-round signals under the heading "Transmission of two-round signals," next operation of the system under certain circumstances causing transmission of a different type of signal under the heading "Transmission of three-round signals," and finally in connection with restoration of normal conditions for certain equipment under the heading "Restoration after two-round signals."

Normal operation

Let it be assumed that the signaling system is in the condition shown in the drawing wherein it will be seen that burner motor contacts 31 are

open with the result that potential is applied to the grid of section S1 of tube 25, causing energization of winding B1 through the circuit including the contact 33 of this relay. Likewise, the relay A is energized, closing its contact A1. Since relay B has one winding B1 energized, it follows that both the contact 33 and the contact 47 will be closed.

When the control thermostat CT of the unit operates to cause starting of operation of the unit, contacts 31 close, energizing the motor from the source of 110 volts A. C. and shunting the transformer 30. The secondary voltage of transformer 30 immediately drops to zero with the result that positive half cycles of voltage are no longer applied to the grid of section S1 of tube 25. Consequently, this section stops passing current and the winding B1 of relay B is deenergized, breaking its own circuit at the contact 33 and likewise breaking the connecting link between the grid and cathode circuits of section S2 of tube 25 at contact 47. When the latter occurs, the voltage on the grid of section S2 does not drop to zero immediately due to the fact that condenser 42 is in a charged state, as previously described. This condenser starts discharging through the resistor 41 and such sections of the switch 40 as may be in series therewith, depending on the position of the contact pointer 40'. Since the resistor 41 is of such large value as before described and may have added thereto resistor sections of switch 40, a considerable length of time may be required for full discharge of condenser 42 to take place. As the charge on condenser 42 diminishes, the voltage of the grid more nearly approaches zero and becomes, therefore, more negative with respect to the cathode of section S2. This decrease in the voltage on the grid causes a slow reduction in the current passed from the plate to the cathode of section S2 and, if this reduction continues long enough, it will result in the plate-cathode current falling below that value necessary to maintain relay A energized.

However, during this reduction of current passing through relay A, and before relay A is de-energized, under normal operation the flame detector, if ignition is of a satisfactory character, will have closed its contacts at the point marked FD. Closure of these contacts establishes a circuit from local source of D. C. through the contacts FD, line 24, winding B2 of relay B, and return to source of D. C. over line 22, thereby energizing relay B and causing both contacts 33 and 47 to close. Closure of contact 47 reestablishes the connecting link between the grid and cathode circuits of section S2, causing the condenser 42 to again become charged and restoring cathode potential to the grid in the manner before described with the result that full plate cathode current flows through section S2 of tube 25. The timing cycle, determined by the interval necessary for discharge of condenser 42, is interrupted, and the transmitter 10 remains energized, since the plate cathode current through relay A did not reach such a low value as to cause this relay to fall back and open contact A1. Consequently, no signals were transmitted by transmitter 10, since the flame detector had operated, indicating normal ignition and combustion.

When the unit control thermostat operates to stop operation of the unit, contacts 31 are opened and transformer 30 immediately reenergized with the result that section S1 starts passing current (since contact 33 was closed upon energization of

winding B2). Flow of current through section S1 again energizes the winding B1 of relay B, creating a condition similar to that existing at the start of operation. After a short time, during which the heat requirement has been satisfied, the flame detector contacts FD will open, thereby opening the circuit to winding B2, but contacts 33 and 47 will remain closed, since winding B1 has been energized upon energization of transformer 30. As a result of this operation, the signal system is restored completely to its initial condition and, as before stated, no signals of any type were transmitted.

Transmission of two-round signals

Should the fuel being supplied to the unit fail to ignite when the unit starts operation and the safety controls of the unit fail to operate in their intended fashion, then the action described under the heading "Normal operation" will take place to the point at which the flame detector contacts FD should close. Under the assumption made, however, that normal ignition did not take place, these contacts would not close, and therefore winding B2 of relay B would not be energized from the local source of DC. As a result of failure to energize winding B2, the timing cycle determined by discharge of condenser 42 will continue until the grid of section S2 of tube 25 becomes so negative with respect to the cathode of this section that the current passed by section S2 is not sufficient to maintain relay A in such state of energization as to hold contact A1 closed. When this state is reached, contact A1 opens instantaneously, breaking the direct current circuit energizing the holding coil 12 of transmitter 10 and, as explained previously, such deenergization of this holding coil immediately releases the wheel 11 so that it begins rotation and continues rotation through two complete circuits or rounds, transmitting two rounds of code signals to the central office. At the same time contact A1 opened, contact A2 closed, establishing the branch circuit between the cathode of section S1 and the return line 35, through winding B1 of relay B, but since section S1 is not passing current at this time the establishment of this circuit has no effect on winding B1.

Should ignition and combustion of the fuel be satisfactory at the beginning of operation of the unit but such ignition and combustion fail prior to the control thermostat reaching its cut-off point without the safety controls operating in their normal fashion, the action of the supervisory signal system will be the same as described under "Normal operation" up to and including the point at which closure of the flame detector contacts FD energize winding B2 of relay B. When ignition and combustion fail, contacts FD will open, opening the circuit of winding B2, causing contacts 33 and 47 to again open even though a circuit had been established which could energize winding B1 but which does not so act due to section S1 failing to pass current therethrough. This failure is caused by zero potential on the grid of section S1 due to operation of the unit motor. When relay B1 is deenergized as just explained, opening of contact 47 starts the timing cycle of condenser 42 discharge in the same manner as previously described, and at the expiration of this timing cycle or retard period relay A will be deenergized and transmitter 10 will operate to transmit two rounds of code signals.

In addition to the operation of the system in

conjunction with the flame detector contacts as just described, two rounds of code signals can be transmitted by transmitter 10 should any one of the three control elements labeled "Low water cut-off," "Pressure switch," and "Thermostat" operate in such manner as to open their respective contacts. Such operation immediately breaks the D. C. holding circuit for holding coil 12, which circuit extends through line 21, the governing devices before mentioned, contact A1 of relay A and line 22. Under these conditions the transmitter 10 will function in its usual manner, causing wheel 11 to make two complete circuits of rotation and send two rounds of code signals. This will take place regardless of the state of the supervisory control circuit in its association with the flame detector or the manner in which the burner unit is otherwise functioning.

Similar signals of two-round duration will be transmitted should the control circuit power supplying sections S1 and S2 of tube 25 fail for a period of several seconds or more. Failure of this power naturally deprives these two sections of current with the result that relays A and B will both be deenergized, and upon the opening of contact A1 the D. C. circuit to the holding coil of the transmitter is opened, causing the transmitter to operate for the desired transmission of signals.

All of the conditions described under this heading will cause two-round signals to be sent by the transmitter, and in addition this mechanism is capable of fully supervising itself and its associated wiring so that two-round signals are transmitted to indicate to the central office the existence of abnormal conditions. In other words, a blown fuse, a defective transformer winding, a burned out tube, a defective relay, or transmitter winding, failure of the local source of D. C. supply, or faults occurring in any of the external wiring except that between the terminals of the contacts marked FD would immediately result in two-round code signals being transmitted. A fault occurring in the external wiring to the terminals of the contacts marked FD would be effective to cause the transmission of this desired signal as soon as the unit started operation, since these contacts are effective only during ignition and combustion of the fuel.

Transmission of three-round signals

This signaling system operates to transmit three rounds of signals in the event the safety controls of the unit function in their normal manner or if the control power (the A. C. source) fails for from one to five seconds. A failure of this control power for less than one second's duration normally should have no effect on the system, since the condensers 37 and 45 are sufficiently large to hold charges which can, in discharging, hold relays B and A energized for that length of time. Safety controls may be of various types, illustration of one of which can be found in Schneider Patent No. 2,293,474, issued August 18, 1942, for "Control for automatic heating systems," in which relays are provided to prevent overloading of an oil burner compressor motor or ignition transformer, such relays in turn controlling the energization of another relay which when deenergized opens the motor circuit.

When the safety controls of the unit operate after start of unit operation, the result is that transformer 30, which is deenergized for such

length of time as is necessary to permit these controls to operate, is then reenergized when the contacts 31 open by action of the safety controls. When a safety control such as a relay for preventing overloading of the ignition transformer operates, the result is to open the motor energizing circuit thereby permitting deenergization of the transformer 30. This same temporary deenergization of transformer 30 occurs on a short control power failure. When transformer 30 is deenergized, winding B1 of relay B likewise is deenergized in the manner described under "Normal operation," opening its own contacts 33 and 47 and starting the timing or retard cycle by the opening of the latter. The flame detector would not close its contacts, however, if improper ignition and combustion of fuel took place, causing the safety controls to operate, reenergizing transformer 30. When transformer 30 is reenergized relay B cannot be energized immediately through either one of its coils because its energizing circuits are open at contacts A2 and 33, and also at FD. Consequently, the timing or retard cycle continues uninterrupted until relay A deenergizes in the manner previously described. When this occurs, contact A1 immediately opens, causing transmitter 10 to be operated to send two rounds of signals as previously described. Simultaneously, contact A2 is closed, completing the circuit from the cathode of section S1 through winding B1 of relay B, and since this tube is now in condition to pass current, winding B1 will be energized, picking up both contacts of relay B. Closure of contact 33 in effect shunts the circuit through contact A2 so that relay B will remain energized when contact A2 is opened. Contact 47 in closing restores the connecting link between the grid and cathode circuits of section S2 of tube 25, causing condenser 42 again to become charged. While this happens in rapid sequence after relay A first is deenergized, the presence of the resistor 49 in the connecting link reduces the charging current to condenser 42 to such an extent that it takes approximately one second for that condenser to charge sufficiently to restore the potential of the grid of section S2 to a value which will permit sufficient plate cathode current to flow through section S2 and through relay A to energize the same. This delay in recharging of condenser 42, therefore, is of such duration that relay A cannot pick up before transmitter 10 has actually started its operation or rotation of wheel 11 thereon, and slight creep only of the transmitter without full release thereof, as might occur if relay A picked up too quickly, is prevented. Relay A being again energized, closing contact A1, it follows that the holding coil of the transmitter 10 is reenergized. However, the transmitter continues its two rounds of rotation of wheel 11 and then immediately continues through a third round of rotation, since the arresting cam follower has been moved from its position in which it could arrest motion after two rounds concurrently with energization of the holding coil 12. It is now in a position preparatory to arresting rotation of wheel 11 at the end of an additional round of rotation. This sequence or cycle of operation, therefore, causes three rounds of code signals to be transmitted to the central station, indicating clearly to that station that the unit is in such condition as to require manual restarting, since its safety control circuits or equipment have been operated, or

that a power failure of short duration has occurred, making checking of the unit advisable.

Restoration after two-round signals

After a two-round signal has been transmitted to the central office and the system is subsequently restored to normal, a single round of signals will be transmitted to the central office due to the reenergization of the holding coil 12.

Similarly, should either of the three devices in series with the holding coil 12, such as the low water cut-off, pressure switch, or thermostat, open to cause the transmission of a two-round signal, closing of the same device will reenergize the holding coil 12 and cause it thereby to effect the transmission of a one-round restoration signal.

In addition to the supervision afforded by the devices in series with the holding coil 12, other services can be rendered by means of the three devices labeled "supervisory devices" shown in series with the transmitter 17. While three such members have been shown, it will be apparent that any number may be used. Opening of the contacts of any one of these devices will cause the transmission of a two-round signal by transmitter 17, and likewise closing of a once opened device will cause this same transmitter to send its one-round restoration signal.

From the foregoing it will be seen that the present invention provides novel and efficient means for so supervising the operation of a fluid burner unit as to make possible the transmission of signals to a central office with the signals being of various distinctive characters to indicate approximately to that office the difficulty existing at the unit. It will be understood that the invention is capable of modification beyond the illustrated embodiment, and consequently any limitations to be imposed upon the same are only those set forth in the following claims.

What is claimed is:

1. The combination with a fluid fuel burner

unit of a code signal transmitter, a relay governing said transmitter and holding it inoperative to transmit signals while the relay is energized, a space current path normally energizing said relay, a normally closed link circuit for said space current path, said link circuit being opened by start of operation of said unit, retard means activated by opening of said link circuit for decreasing current through said space current path and said relay until said relay is deenergized at the end of a predetermined interval to release said transmitter for transmission of signals, and means responsive to successful fuel ignition for closing said link circuit to arrest decrease of current through said path and said relay prior to deenergization of said relay to prevent transmission of signals.

2. Supervisory means for a fluid fuel burner unit comprising a pair of space current paths, a 20 relay operated by the first of said paths, a second relay operated by the second of said paths, control means for said second path governed by said first relay, means whereby current flow through said first path is interrupted by start of operation 25 of said unit causing said control means to interrupt current flow through said second path at the end of a predetermined interval, and a code signal transmitter having a control circuit and a signalling circuit, said transmitter being driven independently of the power energizing said unit 30 and having its control circuit so controlled by said second relay that interruption of current flow through said second path causes transmission of a distinctive code signal.

3. A supervisory system in accordance with claim 2 having a flame detector device, means for so connecting said flame detector to said first relay that operation of said flame detector upon proper fuel ignition energize said first relay thereby to arrest action of said control means prior to the end of said predetermined interval.
